CLAIM

The ornamental design for a handset, as shown and described.

DESCRIPTION

FIG. 1 is a bottom plan view of a handset showing my new design;

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a perspective front view thereof;

FIG. 8 is a perspective rear view thereof;

FIG. 9 is a right side view thereof shown in an open position;

FIG. 10 is a front view thereof shown in an open position;

FIG. 11 is a left side view thereof shown in an open position;

FIG. 12 is a perspective front view thereof shown in an open position; and,

FIG. 13 is a perspective rear view thereof shown in an open position.

The broken line showings in an interior portion of FIG. 13 are for illustrative purposes only and form no part of the claimed design.
